ATTORNEY

UNITED STATES PATENT OFFICE

JOHN G. MUELLER, OF DAYTON, OHIO

RAILWAY-TRACK-TYING DEVICE

Application filed September 27, 1928. Serial No. 308,695.

This invention relates to railway track tying devices for clamping and gripping the rails to prevent spreading and creeping of the rails.

5 The object of the invention is to provide a railway track tying device which will clamp the rails with a vice-like grip so as to produce a unitary structure of the two rails and prevent any movement of the rails with respect 10 to each other; which will have few parts; which will be inexpensive to manufacture and easily assembled inasmuch as the parts are interchangeable; which will be universal, that is, applicable to standard track rails of various sizes; which will have means for permitting the taking up of any wear of the parts, thus adding to the life thereof; and which 15 may be used instead of any track brace now on the market, such as the old fashioned tie rod, antirail spreader, tiltar and creeper.

To secure the foregoing results I utilize a single block for engaging the bottom of the base of the rail and two locking members adapted to engage such block and the rail base 25 flange with means for adjusting the members to various sizes of rails.

In the accompanying drawings, Fig. 1 is a view showing my invention applied to a railway track, the rails being in section and the 30 track tying device in elevation; Fig. 2 is a sectional view of my track tying device applied to a rail; and Fig. 3 is an elevation of one of the locking members with the tie rod in section.

35 In the drawings the invention is illustrated as applicable to standard track rails of various sizes but it will readily be understood that it may be made applicable to the smallest rails used on any tracks in existence.

40 Referring to the drawings, and more particularly Fig. 1, I have shown a section of the usual railway track arrangement comprising parallel rails 1 and 2. A tie bar or rod 3 extends beneath the track from a point beyond the outer edge of one rail to a point beyond the outer edge of the other rail, and is screw-threaded at either end, as shown at 4, to permit of adjusting, clamping and locking members 5 on both sides of the base flange of 45 each rail.

Coacting with the locking members 5 is an angular shaped block 6 having an upper flat surface 7 adapted to contact with the bottom of the rail base when clamped in position. The block 6 is provided with a circular opening 8 adapted to receive the tie rod 3.

55 The locking members 5 and block 6 are each provided with cam surfaces 9 and 10, respectively, which are brought into engagement one with the other when the device is applied to a rail, the locking members forcing the block against the base of the rail by reason of the sliding relation of the inclined surfaces. To effect the sliding of the parts in order to cause them to grip the rail the locking members 5 are provided with elongated openings 60 11 to receive the tie rod 3, thereby providing for up and down movement of the locking members with respect to the tie rod.

65 Each locking member 5 has a hook-like portion having an under inclined surface 12 adapted to grip the upper portion of the rail base flange, producing what may be termed a taper-grip. An opening or recess 13 formed between the under inclined surface 12 and the upper surface 13^a of the lower portion of the member 5 is of such size as to receive a wide variety of sizes of rail base flanges and always leave a space between the outer edge 70 14 of the rail base flange and the vertical wall 15 of the recess 13. By means of this construction the device may be used on a 55 pound rail and a 136 pound rail with perfect satisfaction and any wear of the parts may be taken up by advancing the locking members 5 on the rail, due to the space that is left between the outer edge of the rail base flange and the vertical wall of the recess even when the device is applied to the smallest sized 75 rails.

80 It will readily be apparent that the device to withstand the strains and stresses and provide the necessary gripping action must be very strong. To that end I have provided the members 5 with strengthening ribs 16 and 17 on the upper surface and 18 on the lower surface, the latter coacting with a lock washer 19 which is held in place by a lock nut 20.

85 100 It will be noted by reference to Fig. 2 that the rail base is not only gripped by the mem-

bers 5 but that these members in conjunction with the block 6 clamp the rail base so that there is no chance of any movement of the rail up or down or sidewise. Thus when a 5 railway track is suitably equipped with a sufficient number of my devices there will be no spreading of the rails which according to all commissioners' reports within the last ten years has been the largest factor in all the 10 great railroad catastrophies, and especially is this true where a road has a number of curves, some of which are very sharp and very difficult and expensive to properly maintain.

15 Thus it will be seen that the sliding relation of the block 6 and members 5 with respect to one another and of the members 5 with respect to the rail make the device as a whole adaptable to rails of different 20 weights. In other words, I have provided a track tying device that is universal in that the same device may be applied to rails of different weights and different types or styles. For instance, the same device may 25 be applied with equal success on a track constructed of 55 pound rails or 136 pound rails, or on a track constructed of rails of the style called A. S. C. E. or A. R. A. type A or A. R. A. type B.

30 A further advantage of my device is the complete interchangeability of the parts inasmuch as any member 5 may be placed on either side of the block 6. These features, together with the fact that the device comprises 35 so few parts, make for great economy as well as convenience.

The effect of the relation of the block 6 and locking members 5 when assembled on the tie rod and forced into engagement 40 with the rails is to clamp the same with a vice-like grip, thereby tying the rails firmly against forward or backward or sidewise movement and providing an absolutely safe track.

45 While I have shown one form of construction of my invention, it is obvious that modifications may be made thereof without departing from the principle of construction and application.

50 Having thus fully described my invention, what I claim as new and desire to secure by Letters Patent, is:

1. In a railway track tying device, the combination with a tie rod, of a single block 55 disposed on the tie rod and adapted to engage the bottom of the rail base, locking members also disposed on the tie rod and adapted to engage the top of the rail base flange and coact with the block to clamp the 60 rail with a vice-like grip, means for adjusting the locking members and block and maintaining them in gripping position and means to allow for further adjustment in case of wear of the parts.

65 2. In a railway track tying device, the com-

bination with a tie rod, of a block disposed on the tie rod and adapted to grip the base of the rail, and locking members also disposed on the tie rod and each having an inclined surface adapted to grip the upper portion of the rail base flange in such a manner as to leave a space between the outer edge of the rail base flange and the locking member to provide for further adjustment of the locking member in case of any wear of the 75 parts.

3. In a railway track tying device, the combination with a tie rod, of a block disposed on the tie rod and adapted to grip the base of the rail, locking members also disposed on the tie rod, each locking member having an inclined surface adapted to grip the upper portions of the rail base flange, and means for adjusting the parts to gripping position, each locking member having a 80 cut away portion to provide a space between the outer edge of the rail base flange and the locking member so that the locking member may be advanced on the rail in case of any 85 wear.

4. In a railway track tying device, the combination with a tie rod, of a block disposed on the tie rod, and locking members also disposed on the tie rod on either side of said block, the upper surface of the block adapted to grip the bottom of the rail and the sides being inclined to form cam surfaces, each of said locking members having a cam surface adapted to coact with the adjacent cam surface of said block and having a hook-like member with an inclined surface adapted to grip the top of the rail base flange, and means for adjusting to and maintaining in gripping position the locking members and block, and means to allow for further adjustment in case of wear of the parts.

5. In a railway track tying device, the combination with a tie rod, of a block disposed on the tie rod, and locking members also disposed on the tie rod on either side of said block, the upper surface of the block adapted to grip the bottom of the rail and the sides being inclined to form cam surfaces, each of said locking members having a cam surface adapted to coact with the adjacent cam surface of said block and also having a hook-like member with an inclined under surface adapted to grip the top of the rail base flange, and each locking member further having a cut-away portion 100 to provide a space between the outer edge of the rail base flange and the locking member so that the locking member may be further 105 adjusted in case of wear.

6. In a railway track tying device, the combination with a tie rod, of a block disposed on the tie rod, locking members also disposed on the tie rod on either side of said block, the upper surface of the block being 110 adapted to grip the bottom of the rail and the 115

sides thereof being inclined to form cam surfaces, each of said locking members having a cam surface adapted to coact with the adjacent cam surface of said block and also having a hook-like member with an inclined under surface adapted to grip the top of the rail base flange, and means for adjusting to and maintaining in gripping position the locking members and block, and means to allow for further adjustment in case of wear of the parts.

7. In a railway track tying device, a locking member having a vertically elongated opening, a hook-like portion forming a recess, the lower surface of the hook portion being inclined, a cam surface extending from the lower portion of said recess to the bottom of the locking member, and a rib on the bottom of the member at the outer edge thereof.

8. In a railway track tying device, the combination with a tie rod, of a block having inclined surfaces and an opening extending therethrough to receive the tie rod, the upper surface of said block being adapted to grip the bottom of a rail, locking members each having a vertically elongated opening to receive the tie rod and an inclined surface adapted to coact with one of the inclined surfaces of said block, each locking member also having a hook-like portion, the lower surface of which is inclined to grip the upper portion of the rail base flange in such a manner as to leave a space between the outer edge of the rail base flange and the locking member to provide for taking up any wear of the parts.

9. In a railway track tying device, the combination with a tie rod, of a block having inclined surfaces and an opening extending therethrough to receive the tie rod, the upper surface of said block being adapted to grip the bottom of a rail, locking members each having a vertically elongated opening to receive the tie rod and an inclined surface adapted to coact with one of the inclined surfaces of said block, each locking member also having a hook-like portion, the lower surface of which is inclined to grip the upper portion of the rail base flange in such a manner as to leave a space between the outer edge of the rail base flange and the locking member to provide for taking up any wear of the parts, reinforcing ribs on said locking member, a lock washer, the lower portion of which engages one of the reinforcing ribs, and a lock nut for each locking member.

10. In a railway track tying device, the combination with a tie rod, of a plurality of sets of locking members disposed on the opposite sides of two opposite rails, a block coacting with each set of locking members, and means for adjusting the members and block with respect to the rails to grip them on the top and bottom of the base flanges thereof, said locking members each having

a rib on the under surface coacting with the adjusting means.

11. In a railway track tying device, the combination with a tie rod, of a plurality of sets of locking members disposed on the opposite sides of two opposite rails, a block coacting with each set of locking members, means for adjusting the members and block with respect to the rails to grip them on the top and bottom of the base flanges thereof, and means to allow for further adjustment in case of wear of the parts.
